ATTORNEY

UNITED STATES PATENT OFFICE.

WILLIAM C. WINFIELD, OF WARREN, OHIO, ASSIGNOR TO THE WINFIELD
MANUFACTURING COMPANY, OF SAME PLACE.

DESIGN FOR A CAN.

SPECIFICATION forming part of Design No. 22,518, dated June 6, 1893.

Application filed April 29, 1893. Serial No. 472,434. Term of patent 7 years.

To all whom it may concern:

Be it known that I, WILLIAM C. WINFIELD, a citizen of the United States, and a resident of Warren, in the county of Trumbull and State of Ohio, have invented and produced a new and original Design for Cans, of which the following is a full, clear, and exact description, reference being had to the drawing making part of this specification.

10 The design is illustrated in the accompanying drawing in a single perspective view of the can.

The can shown is distinguished chiefly by the appearance of the top which has wide dome shaped portion —a— rising from the narrow flat surface —b— about the base of the dome; the raised edge —c— at the immediate edge of the can—the inner raised outer edge —d— where the border surface —a—

terminates, the deep depression central in 20 the top having flat surface —g—, and a vertical wall —e— about said depression terminating in the edge —d—, the flat surface —g— having holes or openings —h— and —k—, varying in size and off the center of the said 25 depression. A dish shaped lid or cover for the inner part of the top is shown in raised position to reveal the appearance of the whole top.

Having thus described my invention, what 30 I claim as new, and desire to secure by Letters Patent, is—

The design for a can as described and shown.

WILLIAM C. WINFIELD.
